UNITED STATES PATENT OFFICE.

ALFRED H. HUMPHREY OF NEW YORK, N. Y.

DESIGN FOR A RADIANT FOR GAS-STOVES.

59,964.

Specification for Design.

Patented Dec. 13, 1921.

Application filed February 15, 1921. Serial No. 445,270. Term of patent 14 years.

To all whom it may concern:

Be it known that I, ALFRED H. HUMPHREY, a citizen of the United States, and a resident of the city and county of New York, State of New York, (whose post-office address is 44 West Broadway, New York city,) have invented a new, original, and ornamental Design for a Radiant for Gas-Stoves, of which the following is a specification, reference being had to the accompanying draw-

ing, forming a part thereof, which is a front elevation showing my new design.

I claim:

The ornamental design for a radiant for gas stoves, as shown.

ALFRED H. HUMPHREY.
